UNITED STATES PATENT OFFICE

WILLIAM M. ADRIAN, OF CHICAGO, ILLINOIS

DESIGN FOR A COMBINED STANDARD AND LAMP BASE

Application filed July 15, 1931. Serial No. 40,552. Term of patent 3½ years.

To all whom it may concern:

Be it known that I, WILLIAM M. ADRIAN, a citizen of the United States, residing at Chicago, in the county of Cook and State of Illinois, have invented a new, original, and ornamental Design for a Combined Standard and Lamp Base, of which the following is a specification, reference being had to the accompanying drawing, forming part hereof.

The figure is a partial side elevation of a combined lamp base and standard, show-

ing my new design, the remaining portion being indicated in dotted lines and being identical with the portion shown in full lines.

The opposite sides and the conformation of the combined base and standard are the same as that illustrated in the drawing.

I claim:

The ornamental design for a combined standard and lamp base as shown and described.

WILLIAM M. ADRIAN.
